UNITED STATES PATENT OFFICE.

PHILIP H. SHUE, OF OURAY, COLORADO.

EXPANSIBLE PULLEY.

SPECIFICATION forming part of Letters Patent No. 718,800, dated January 20, 1903.

Application filed March 24, 1902. Serial No. 99,695. (No model.)

To all whom it may concern:

Be it known that I, PHILIP H. SHUE, a citizen of the United States, residing at Ouray, in the county of Ouray and State of Colorado,

5 have invented certain new and useful Improvements in Expansile Pulleys; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 This invention relates to expansile pulleys, and particularly to that class thereof in which the expansion of the rim-segments is produced by the use of a disk having a spiral groove.

20 The object of my invention is to generally improve such pulleys by a construction permitting expansion or contraction of the pulley without stopping its rotation and irrespective of its velocity.

25 A further object is to provide expansion mechanism suitable for a split pulley, inasmuch as it is not known to me that a split pulley has ever been provided with an expansion device. This is very desirable, as 30 the use of split pulleys is advantageous and common.

A further object is to construct an expansion-pulley which will remain at adjustment without strain on the adjusting mechanism 35 until such mechanism is actuated voluntarily.

A further object is to construct a slow-action adjusting device so that it may be used on high-speed shafting.

40 A further object is to provide adjusting devices which will be automatically operated by the revolution of the pulley to expand or contract the same irrespective of the direction of rotation.

45 A further object is to provide automatic stops for the adjusting device, so as to not wreck the same by too great expansion or contraction. This is desirable, since the expansion mechanism is driven by the rotation of the pulley while held in gear by hand, and 50 the eye might not detect the limit in a rapidly-rotating pulley.

With these and other objects in view an embodiment of my invention is hereinafter described and is illustrated in the accompanying drawings, in which—

55 Figure 1 is a side elevation, half in transverse section, of the pulley, a hand shifting-lever being removed. Fig. 2 is a longitudinal section of the shaft and pulley. Fig. 3 is an elevation showing the manner of assembling the grooved disks. Fig. 4 is a fragmentary section showing the stop for the adjustment.

60 Referring specifically to the drawings, the main shaft is indicated at 6. For convenience in assembling and attaching to the shaft the pulley-frame is formed of two side sections 7, each of which is halved or split. The halves are joined in the usual manner, as by bolts 8. Each section has a hub portion 7^a 65 and flange 7^b, which respectively abut, except where the flanges are cut away to permit the passage of the stems 9^a of the segments 9. The sections are held together by bolts 7^c and have radial slots 7^d, in which slide 75 lugs 9^b on the segments to guide the radial movement thereof.

70 The adjusting-disks 10 are mounted in easy contact with and revolute on the hub between the side sections of the pulley. The 80 disks have faced complementary spiral grooves 10^a, which receive lugs 9^c, formed on the inner ends of the segment-stems. As shown in Fig. 3, each disk is split or halved, and in assembling the joints are broken by a 85 quarter-turn and the parts joined by screws 10^b, forming a continuous groove in each disk. The disks bear against the hub of the pulley and form a stout and rigid support for the segments. The disks are turned by the action 90 of shifting-rings 11. These fit loosely over the hub of the pulley and are connected by gearing with the disks. The rings and gearing are duplicated on opposite sides of the pulley to turn the disks in opposite direction 95 and produce contraction or expansion, as desired, irrespective of the direction of rotation of the pulley. They are placed on opposite sides of the shaft to balance the pulley. A description of one will suffice for both. Each ring 100 has on its inner face a spiral or worm thread 11^a, which when it is desired to adjust the

pulley may be thrown in mesh with a worm-wheel 12^a by means of a shifting hand-lever 13 to which the ring is attached. When in mesh, revolution of the pulley turns the wheel 12^a and small shaft 12 on which it is mounted, and the motion is communicated to the disks by means of beveled gears 14 and pinion 15, in mesh with an internal gear formed on the rim 16 of the disks.

10 It will be seen that the tangential strain on the pulley is borne by the side sections or frame and the radial strain by the disks, which are made heavy for that purpose. These disks rest on the hub, and there is therefore no tendency to get out of adjustment, and the adjusting gearing normally bears no strain.

15 A stop for the adjusting device is formed by a lever 17, which is pivoted on the side of the pulley, as at 17^a, and has a beveled head 17^b, which is adapted to be thrown in behind and against the adjusting-ring, when it has the effect of forcing the ring out of mesh with the worm-wheel. The lever is operated by rods 17^c, which are connected to the lug 9^b of 20 one of the segments and pass loosely through openings in the tail of the lever. Each of these rods has a stop-collar 17^d on opposite sides of the lever. The rods take the movement of the segment, and the collars are so set that 25 when the limit of expansion or contraction is reached one of them strikes the lever and throws its beveled head against the ring, forcing the latter out of mesh. It is to be understood that there is one of these stops on each side of the pulley for each ring.

30 My invention is not limited to the exact construction herein shown and described; but

What I claim is—

1. The combination with a pulley-frame 40 and rim-segments guided radially thereon, of adjusting-disks having a spiral groove and engaging the segments.

2. The combination with a pulley-frame having radial guide-slots, of rim-segments 45 having lugs in said slots, and spirally-grooved adjusting and supporting disks for the segments.

3. The combination with a pulley-frame and rim-segments guided radially thereon, of 50 spirally-grooved adjusting-disks for the segments revolubly relative to the frame.

4. The combination with a pulley-frame and rim-segments guided radially thereon, of 55 spirally-grooved adjusting-disks for the segments revolubly supported on the hub of the frame.

5. The combination with a pulley-frame comprising two detachable side sections, and 60 radially-movable rim-segments between the same, of spirally-grooved revoluble disks be-

tween the sections adjustably supporting the segments.

6. The combination with a pulley-frame comprising two side sections detachably joined, and radially-guided rim-segments between the same, of spirally-grooved adjusting-disks for the segments revoluble on the hub between the sections. 65

7. The combination with a pulley-frame comprising two side sections detachably joined, and radially-guided rim-segments between the same, of two joined disks revoluble between the sections, having faced complementary spiral grooves in which projections on the segments are supported. 70

8. The combination with a pulley-frame, radially-guided rim-segments thereon, and revoluble spirally-grooved adjusting-disks for the segments, of means to revolve the disks, and means actuated by the movement 80 of the segments to stop the disks.

9. In an expansible pulley, in combination, a pulley-frame, having radially-movable rim-segments, gears to move the segments, and means actuated by the movement of the segments to automatically disengage said gears and stop the movement. 85

10. In an expansible pulley, the combination with a pulley-frame having radially-movable rim-segments and means to move the 90 same, of an automatic stop for the said means connected to one of the segments.

11. In an expansion-pulley, in combination, a pulley-frame, radially-guided rim-segments thereon, spirally-slotted disks revoluble relative to the frame and engaging the segments, gears to revolve the disks, and levers connected to the segments and actuated thereby to disengage the gears at the limit of expansion or contraction. 95

12. In an expansion-pulley, in combination, a pulley-frame, spirally-grooved revoluble adjusting-disks, radially-movable rim-segments guided by the frame and engaging the disks, worm wheels and gears to revolve 105 the disks, and shifting rings having a worm-thread engageable with the wheels.

13. The combination with a pulley-frame having radially-movable rim-segments, of oppositely-operating expansion devices on each 110 side of the frame, automatically actuated by the revolution of the pulley, whereby the segments may be expanded or contracted irrespective of the direction of revolution.

In testimony whereof I affix my signature 115 in presence of two witnesses.

PHILIP H. SHUE.
